(57) **CLAIM**

(21) Appl. No.: **29/544,768**

The ornamental design for an electronic probe handle, as shown and described.

(22) Filed: **Nov. 5, 2015**

DESCRIPTION

(51) LOC (10) Cl. 10-04

FIG. 1 is a perspective top view of an electronic probe handle with the electronic probe head used with said electronic probe handle shown in phantom lines;

(52) U.S. Cl. USPC **D10/103**; D8/316; D8/320

FIG. 2 is a top planar view of the electronic probe handle of FIG. 1; and,

(58) **Field of Classification Search** USPC D10/103; D8/306, 316, 320

FIG. 3 is a right side view of the electronic probe handle of FIG. 1, the left side view being a mirror image thereof.

CPC Y10T 16/476; Y10T 16/55; Y10T 16/4554;

The broken lines are included for the purpose of illustrating a portion of the electronic probe handle that form no part of the claimed design.

Y10T 16/4567; Y10T 16/4569

See application file for complete search history.
